SPRAY HEAD

Jordan I. Rotheiser, Highland Park, Ill., assignor to Selfix, Inc.

Filed Dec. 21, 1970, Ser. No. 26,575

Term of patent 14 years

Int. Cl. D23—01

U.S. Cl. D23—35

FIG. 1 is a perspective view of my new design for a spray head;

FIG. 2 is a bottom view thereof;

FIG. 3 is a side elevation view thereof;

FIG. 4 is a front elevation view thereof;

FIG. 5 is a rear elevation view thereof; and

FIG. 6 is a plan view thereof.

I claim:

The ornamental design for a spray head, as shown.
